Specification of Letters Patent. Patented Dec. 10, 1918.

Application filed November 27, 1915. Serial No. 63,711.

To all whom it may concern:

Be it known that I, MORGAN PARKER, a citizen of the United States, residing at Newport, county of Newport, and State of Rhode Island, have invented certain new and useful Improvements in Detachable-Blade Knives; and I do hereby declare the following to be a full, clear, and exact description of the invention, such as will enable others skilled in the art to which it appertains to make and use the same.

This invention relates to detachable blade knives and more particularly to the construction of the devices whereby the blade is detachably held upon the handle of the knife. The object of the invention is to provide such an improved construction of the parts by which the blade is held upon the handle that a compact, neat, slight and inexpensive structure is produced which will hold the blade firmly against movement upon the handle and which permits of attaching and detaching the blade easily and quickly.

The invention may be employed in knives and razors of various types but I have found it to be of special utility in surgical instruments of the type known as surgeons' scalpels.

I have illustrated the preferred embodiment of my invention in the accompanying drawings in which Figure 1 is a perspective view of the knife; Fig. 2 is a similar view with the blade partially detached; Fig. 3 is a perspective view of the end of the handle; Fig. 4 is a plan view of the handle with the blade thereon; Fig. 5 is a longitudinal section on the line 5—5 of Fig. 4; and Figs. 6 and 7 are transverse sections on the lines 6—6 and 7—7 of Fig. 4.

Referring to these drawings, the handle of the knife consists of a hand-grip 8 and a blade-support 9 projecting from the end of the grip. This blade-support at its end adjacent to the grip has a plane surface upon which the inner end of the blade bears and beyond this is a projection 10 raised from the surface of the blade-support, thus forming in effect a connecting portion having a flat bottom recess between the projection 10 and the hand grip 8. This projection 10 is preferably elongated in the direction of the length of the knife and provided with rounded ends as shown. In the sides of the projection are grooves 11. These grooves extend from the outer end of the

projection 10 to a point about midway of the length of the projection.

The blade is shown at 12. It consists preferably of thin sheet metal cut to the shape best adapted for the use for which the knife is designed and sharpened at its edge, as is indicated in the drawing. The blade has an opening 13 therein. The portion of this opening 13 adjacent to the inner end of the blade corresponds accurately in size and shape to the corresponding portion of the projection 10, that is, the portion of the projection 10 which is not provided with grooves in its sides. The remainder of the opening in the blade 12 is of less width, as is indicated by the dotted lines 14 in Fig. 4.

In order to mount the blade upon the handle, the outer end of the projection 10 is introduced into the wider portion of the opening 13 in the blade and the walls of the opening 13 at the point where the width of that opening is decreased are introduced into the grooves 11 in the sides of the projection 10. This is best done by grasping the outer end of the blade between the thumb and forefinger and the blade is then subjected to a slight rocking movement which brings the inner end of the blade down upon the top surface of the projection 10 and flexes the blade slightly in the direction of its length. This slight movement of the blade is sufficient to bring the walls of the narrower portion of the opening 13 into alignment with the grooves 11 in the projection 10. The blade may then be moved toward the hand-grip 8 and the walls of the narrower portion of the opening 13 entered into the grooves 11. While passing through this movement, the blade is flexed very slightly in the direction of its length since a portion of the blade is held parallel to the length of the grooves 11, whereas the inner end of the blade near the inner end of the opening 13 bears upon the top of the projection 10. The parts are then in the condition in which they are shown in Fig. 2. At the end of the movement of the blade in this direction, this flexure of the blade is relieved by the inner end of the blade passing over the inner end of the projection 10 and down upon the flat surface between 8 and 10 of the recess.

When in this condition, the blade is held firmly against movement in any direction in the plane in which the blade lies, as the projection 10 fits so snugly in the opening

13 in the blade. The instrument may then be used with the same facility as a similar instrument not having capacity for removal of the blade from the handle. Particularly, 5 it will be noted that the means for securing the blade upon the handle includes no lateral projection which might catch upon the substance on which the knife is being used.

At the extreme inner end of the blade the 10 material thereof is extended laterally, as shown at 15, so that when the blade is mounted on the handle this portion 15 will project beyond the edge of the surface 9 sufficient to permit of applying lateral pressure thereto with the finger. To remove the 15 blade from the handle, the extension 15 is moved laterally a slight amount to flex the blade in the direction of its length an amount sufficient to carry the inner end of 20 the blade above the plane of the top surface of projection 10. Then the blade is moved in the direction of its length until the walls of the narrow portion of the opening 13 are withdrawn from the grooves 11 in the projection 25 10.

It will thus be seen that applying the blade to the handle involves flexing the blade slightly in the direction of its length to permit coaction of the walls of the narrow portion of slot 13 and the grooves in projection 30 10. The blade is held in this flexed condition while it is being moved to its final position and then its flexure is automatically relieved by the inner end of the blade dropping over 35 the end of the projection 10. Then the blade is held firmly as the only movement of which it is capable is a bending movement of the inner end of the blade against the tension of the blade itself. To remove the blade, it 40 is flexed by such bending movement of its inner end transverse to the plane in which it lies and the blade may then be moved in the direction of its length to detach it from the handle.

45 What I claim is:

1. A detachable blade knife comprising, in combination, a handle having a hand-grip and an elongated blade-holding projection, a flat flexible blade having an elongated closed 50 slot shaped to closely embrace the projection to prevent movement in all directions in the plane of the blade, and a tongue and groove interlock normally preventing separation of the blade and handle but so positioned as to 55 permit a flexing movement of the blade to clear one end of the projection and a subsequent movement of the flexed blade lengthwise of the projection to disengage the interlock.

60 2. A detachable blade knife comprising, in combination, a handle having a hand grip, and an elongated projection spaced apart from the hand grip and having side grooves extending from one end of the projection for 65 a part of the length thereof; and a flat flexi-

ble blade with a closed slot which has one portion closely surrounding a part of the projection and another portion of restricted width with walls normally fitted in the side grooves to rigidly interlock the blade and 70 handle against relative movement except when the blade is flexed.

3. A detachable blade knife comprising, in combination, a handle having a hand grip, an elongated projection, and a connecting 75 portion having a flat bottom between the upper surface of the projection and the hand grip; and a flat flexible blade with a closed slot closely embracing the projection to prevent relative movement in all directions in 80 the plane of the blade; the blade having a portion which normally rests on said flat bottom and which is capable of transverse flexure, whereby that portion may be lifted above the projection to slide the blade longitudinally out of engagement therewith.

4. A detachable blade knife comprising, in combination, a handle having a hand grip, and a blade support with a single elongated projection spaced apart from the hand grip; 85 and a flat flexible blade with a closed slot embracing the projection and having walls with a part thereof rigidly interlocking with a part of the projection below the upper surface thereof; the blade having a portion 90 capable of transverse flexure, whereby that portion may be lifted above the projection to longitudinally slide the blade out of engagement therewith.

5. A detachable blade knife comprising, in 100 combination, a handle having a hand grip, and a blade support having on its upper surface an elongated projection with side grooves extending from one end of the projection for a part of the length thereof, and 105 also having a connecting portion with a flat bottom on its upper surface between the hand grip and the inner end of the projection; and a flat flexible blade having a closed slot embracing the projection and having at 110 one end a portion of restricted width; the walls of the restricted portion of the slot rigidly interlocking with the grooves in the projection, and the blade having a portion 115 which normally rests on said flat bottom and which is capable of transverse flexure, whereby that portion may be lifted above the projection to slide the blade longitudinally out of engagement therewith.

6. A detachable blade knife comprising, in 120 combination, a hand-grip, a blade-support projecting from the end of the grip and provided with a flat bottomed recess adjacent the end of said grip, and having attaching means associated with each of its sides, a flat 125 blade having an elongated slot extending longitudinally therein, said slotted blade being provided with a portion adapted to fit around said blade support and a portion adapted to engage said attaching means, the 130

recess in said support receiving the end of said blade to permit the blade to be held flat upon said support.

7. A detachable blade knife comprising, 5 in combination, a hand-grip, an elongated blade support projecting from the end of the grip and provided with a flat bottomed recess adjacent the end of said grip and having a groove along a portion of each of its sides, 10 a blade having an elongated slot extending

longitudinally therein, said slot being provided with a portion adapted to fit around said blade-support and a portion adapted to fit within the grooved portion of said support, the recess of said support being adapted to receive the end of said blade to permit the blade to be held flat upon said support. 15

In testimony whereof I affix my signature.

MORGAN PARKER.
